UNITED STATES PATENT OFFICE

172,500

COMBINATION ANTENNA AND PLANTER

William V. Gurmin, Youngstown, Ohio

Application September 30, 1953, Serial No. 27,012

Term of patent 14 years

(Cl. D26—14)

To all whom it may concern:

Be it known that I, William V. Gurmin, a citizen of the United States, residing at Youngstown, in the county of Mahoning and State of Ohio, have invented a new, original, and ornamental Design for a Combination Antenna and Planter, of which the following is a specification, reference being had to the accompanying drawing forming a part thereof.

Figure 1 is a front plan view of a combination antenna and planter, showing my new design.

Figure 2 is a side elevation.

I claim:

The ornamental design for a combination antenna and planter, as shown.
